UNITED STATES PATENT OFFICE.

EMILE LECOULTRE, OF ALEXANDRIA, VIRGINIA, ASSIGNOR TO CHARLES C. CARLIN, OF ALEXANDRIA, VIRGINIA.

TABULATING DEVICE FOR TYPE-WRITING MACHINES.

No. 858,083.

Specification of Letters Patent.

Patented June 25, 1907.

Application filed May 11, 1904. Serial No. 207,429.

To all whom it may concern:

Be it known that I, EMILE LECOULTRE, a citizen of the United States, residing at Alexandria, in the county of Alexandria, State of Virginia, have invented certain new and useful Improvements in Tabulating Devices for Type-Writing Machines, of which the following is a description, reference being had to the accompanying drawing, and to the letters and figures of reference marked thereon.

My invention relates to tabulating devices for typewriting machines, and is particularly adapted for use in connection with typewriting machines of what is known as the Remington type.

In an application filed in the United States Patent Office, March 26, 1904, Serial No. 200,114, I have shown and described a device adapted to be attached to a typewriting machine, or used in connection therewith, for tabulating work comprising a longitudinally movable stop bar provided with a column stop, mounted on the frame of the machine, means for moving the stop bar longitudinally, and a movable stop on the paper carriage normally out of line with the column stop and means for moving the movable stop into position to engage the column stop.

My present invention is primarily designed as an improvement on the invention shown and described in the application referred to and is designed to avoid the necessity of moving the stop carried by the carriage into and out of position to engage the column stop.

The invention is, however, applicable to other forms of tabulating devices, than that shown and described in my application referred to.

With this object in view, my invention consists in providing the stop carried by the carriage with a flexible end section normally in line with the column stop and adapted to normally yield in passing a column stop, and means for so locking the flexible end section when desired, that it will serve to stop the carriage when it comes against a column stop, as hereinafter described and claimed.

Referring to the drawings, Figure 1 is a top plan view of a typewriting machine having my improvement applied to it, Figs. 2 and 3 are side views of the typewriting machine taken from opposite sides, Fig. 4 is a side view partly in section showing the stop car-

ried by the carriage, and Fig. 5 is a perspective view of the stop carried by the carriage. Fig. 6 is a detail plan view showing the arm 16 and its engagement with the tabulating stop bar.

Referring to the parts by reference numerals 1 indicates the frame of a typewriting machine of the Remington type; 2 indicates one of the printing keys; 3 indicates the paper carriage; 4 indicates the guide rod on which the carriage reciprocates; 5 indicates the pinion of the escapement mechanism; and 6 the rack bar carried by the carriage and adapted to be raised out of engagement with the pinion 5; 7 indicates the rearwardly extending arm connected with the rack arranged to come in contact with the marginal stops carried by the stop bar; 8 indicates lugs extending upward from the top plate of the machine supporting the stop bar and guide rod.

The construction so far described is the ordinary construction commonly found in typewriting machines of the Remington type.

Instead of the means ordinarily employed for holding the journals of the guide rod in position on the keys 8, I employ brackets 10 having in their upper ends bearings 11 in which is mounted a tabulating stop bar 12. This bar is shown as a notched bar of ordinary form adapted to receive column stops 13, but may be of any desired construction adapted to carry the column stop. The rearwardly extending arm 7 carries an extension 15 preferably having its end bent over as indicated at 15'. Secured to the rear bar of the carriage is an arm 16 having an end section 17 flexibly connected to it preferably by a hinge joint 18, so constructed that the end section may swing freely in both directions. On the side of the arm 16 is a locking device 19 comprising an arm pivoted at 19' to the arm 16 and having the rear end of its head 19² normally forward of the hinge joint 18 and adapted when operated to be swung rearward against the flexible end section 17 to prevent the latter from swinging in its hinge joint. This locking device is preferably carried on the right hand side of the arm 16 and is held against the arm 16 by a bar 20 secured to the arm 16, between which and the arm, the head of the locking device moves freely.

The locking device 19 has a rearwardly ex-

tending arm 21 preferably having its end bent over as shown at 21'. A spring 22 secured at one end to the arm 16 and at its free end bearing against the rearwardly extending arm 21 serves to hold the locking device 19 normally in retracted position so as to permit the end section 17 to swing freely on its hinge joint 18.

When the locking device is in retracted position the end section 17 will, as the carriage is moved across the machine, come in contact with the column stops, but by reason of its flexible connection with the arm 16 it will yield to the right or left according to the direction of movement of the carriage and will not cause the carriage to be stopped. Depression of the rear end of the arm 21 will cause the locking device to be moved into position to engage the end section 17 to hold it rigid with the arm 16 so that as it comes in contact with a column stop, the carriage will be stopped. Depression of the rear end of the extension 15 will raise the rack bar 6 out of engagement with the pinion 5 to release the carriage and permit it to be carried forward by the feed mechanism until its movement is arrested by contact of the end section 17 with a column stop.

The depression of the arm 21 and the extension 15 is simultaneously effected by means of a rod 24 carried by arms 25 and 26 pivoted to the brackets 10. The arm 26 has a forward extension 26' to which is connected the upper end of a link 27' the lower end of which is connected to a bar 27 extending across the machine and pivotally connected at its ends to clamps 29 secured to the sides of the frame 1. 30 indicates a series of keys preferably arranged above and to the rear of the regular keyboard and pivoted on a shaft 31 carried by clamps 32 secured to the side of the frame of the machine and held in normal position by springs 33 secured to a bar 34 carried by clamps 35 secured to the frame of the machine. The key levers of the keys 30 are arranged to fit between the key levers of the keys 2 and their rear ends 31 are in position to strike against and lift the bar 27. When operated these keys are also preferably arranged to operate a differential mechanism for shifting the rod which carries the column stops longitudinally as described in my application above referred to.

On the operation of one of the differential keys the bar 27 will be raised and through the link 27' and arm 26' will cause the rod 24 to be depressed, pressing downward the end of the extension 15 to release the carriage and simultaneously pressing down the end of the arm 21 to cause the locking device to engage the end section 17 to hold it rigid with the arm 16 so as to cause the carriage to be stopped as the end of the end section 17 comes in contact with a column stop. On the release of the key 30 the spring 22 will re-

turn the locking device to inoperative position permitting the end section 17 to swing to permit the carriage to pass the column stop. Any convenient means may be provided for yieldingly holding the end section 17 in line with the arm 16 such as a pair of light springs 17' arranged one on one side and the other on the opposite side of the arm 16 and any equivalent means of locking the flexible portion of the yielding stop may be employed in place of the means illustrated.

While my invention is particularly intended for use in connection with a differentially operated tabulating machine, such as described in my application before referred to, it will be understood, that it may be used in connection with tabulating devices which are not differentially operated; and also that it may be employed in connection with stop members differently arranged from those illustrated.

The essential feature of my invention is to provide a tabulating mechanism of a typewriting machine having two co-operative stops, said stops being normally inoperative but one of said stops being normally in the path of the other, with means for rendering said stops operative to arrest the carriage.

Having thus described my invention, what I claim as new and desire to secure by Letters Patent, is:

1. A typewriting machine including in combination a carriage, a bar, said elements being respectively provided with an arm and a stop, one of which elements lies in the path of the other and one of which is normally inoperative, and means for rendering operative the normally inoperative element.
2. A typewriting machine, including in combination, a carriage provided with a normally inoperative arm, a bar carrying a stop extending into the normal path of the arm and means for rendering said arm operative.
3. A typewriting machine including in combination a carriage, a bar, said carriage and bar being respectively provided with a stop arm and a stop, the stop being arranged in the path of a part of the stop arm, such part of the stop arm being normally flexible to permit the stop arm to pass the stop and means for rendering such part of the stop arm rigid.
4. A typewriting machine including in combination a carriage, a bar, said carriage and bar being respectively provided with a stop arm and a stop, the stop being arranged in the path of a part of the stop arm, such part of the stop arm being normally flexible to permit the stop arm to pass the stop and key operated means for rendering such part of the stop arm rigid.
5. A typewriting machine including in combination a carriage provided with a stop arm having a flexible end section a stop supported on the frame of the machine in the

path of the end section of the stop arm, and means for temporarily holding the end section of the stop arm rigid.

6. A typewriting machine including in combination a carriage provided with a stop arm having a flexible end section, a stop supported on the frame of the machine in the path of the end section of the stop arm, and key operated means for temporarily holding the end section of the stop arm rigid.

7. A typewriting machine including in combination a carriage provided with a stop arm having a flexible end section, a stop supported on the carriage in the path of the end section of the stop arm, a locking device carried by the stop arm adapted when operated to engage the end section to hold it rigid, and means for operating the locking device.

8. In a typewriting machine and in a tabulating mechanism, the combination of a carriage, a column stop, a co-operating stop, one of said stops being normally in the path of the other and said stops being normally inoperative to arrest the carriage, and means for rendering said stops operative to arrest said carriage.

9. In a typewriting machine and in a tabulating mechanism, the combination of a carriage, a column stop, a co-operative stop, one of said stops being normally in the path of the other and one of said stops being flexible or yielding, and means for locking said flexible or yielding stop so that it may co-operate with the other of said stops to arrest said carriage.

10. In a typewriting machine and in a tabulating mechanism, the combination of a carriage, a stop carried thereby, a co-operative stop on the frame of the machine, one of said stops being flexible, so that though normally in line with the other stop it is inoperative, and means for adapting said flexible stop to co-operate with the other stop to arrest the carriage.

11. In a typewriting machine and in a tabulating mechanism, the combination of a carriage, a column stop, a co-operative stop, one of said stops being normally in the path of the other and said stops being normally inoperative to arrest the carriage, means for rendering said stops operative to arrest said carriage, and a key at the front of the machine adapted to operate said means.

12. In a typewriting machine and in a tabulating mechanism, the combination of a carriage, a column stop, a co-operative stop, one of said stops being normally in the path of the other and one of said stops being flexible or yielding, means for locking said flexible or yielding stop so that it may co-operate with the other of said stops to arrest said car-

riage, and a key at the front of the machine adapted to operate said means.

13. In a typewriting machine and in a tabulating mechanism, the combination of a carriage, a stop carried thereby, a co-operative stop on the frame of the machine, one of said stops being flexible, so that though normally in line with the other stop it is inoperative, means for adapting said flexible stop to co-operate with the other stop to arrest the carriage, and a key at the front of the machine adapted to operate said means.

14. In a typewriting machine and in a tabulating mechanism, the combination of a carriage, a column stop, a co-operative stop, said stops being normally inoperative to arrest the carriage and one of said stops being normally in the path of the other, and means for rendering said stops operative to arrest said carriage.

15. In a typewriting machine, the combination of a carriage, a step-by-step feed device for said carriage, a column stop and a tabulator stop, one of said stops being mounted on the carriage and the other of said stops being mounted on the frame of the machine and standing normally in the path of the stop on the carriage and said stops being normally inoperative to arrest the carriage, a tabulator key, means controlled by said key for rendering said stops operative to arrest the carriage, and means controlled by said key for releasing said carriage from the step-by-step feed mechanism.

16. In a typewriting machine, the combination of a carriage, a column stop and a tabulator stop, one of said stops being mounted on the carriage and the other being mounted on the frame of the machine and normally standing in the path of the stop on the carriage and one of said stops being flexible whereby it is inoperative to arrest the carriage, a tabulator key, a lock for said flexible stop operated by said tabulator key, and a carriage release device also operated by said tabulator key.

17. In a typewriting machine, the combination of a carriage, tabulator stops, one normally in the path of another, but said stops being normally inoperative to arrest the carriage, and means for releasing the carriage and for rendering said stops operative to arrest the carriage.

In testimony whereof I affix my signature, in presence of two witnesses.

EMILE LECOULTRE.
